G. W. REID ET AL

WARP STOP MECHANISM FOR LOOMS.

Filed April 1, 1925

UNITED STATES PATENT OFFICE.

GEORGE W. REID, OF LAWRENCE, AND ALFRED DURAND, OF METHUEN, MASSACHUSETTS, ASSIGNORS TO DRAPER CORPORATION, OF HOPEDALE, MASSACHUSETTS, A CORPORATION OF MAINE.

WARP STOP MECHANISM FOR LOOMS.

Application filed April 1, 1925. Serial No. 19,801.

To all whom it may concern:

Be it known that we, GEORGE W. REID and ALFRED DURAND, citizens of the United States, residing at Lawrence and Methuen, respectively, in the county of Essex and State of Massachusetts, have invented an Improvement in Warp Stop Mechanisms for Looms, of which the following description, in connection with the accompanying drawings, is a specification, like characters on the drawings representing like parts.

This invention relates to warp stop mechanisms for looms, and more particularly to that type comprising an arrestable vibrator with lay knock-off.

In warp stop mechanisms of the above type, it is now customary to provide a dog or fish-tail positioned by arrest of the detector to be struck by a bunter on the lay to effect loom stoppage upon the occurrence of a warp fault. A warp stop mechanism of this general type is shown and described in the patent to Carl D. Brown, No. 1,362,670, December 21, 1920. Since the position of the dog or fish-tail is controlled from the detector, any turning movement of the dog or fish-tail during its engagement with the bunter on the lay is liable to transmit to the detector injurious pressure against the drop wire; and since such drop wires are necessarily made of light material, injury frequently occurs to a drop wire.

An important feature of the present invention, therefore, consists of means for relieving the drop wire from injurious pressure by the detector due to movement of the dog or fish-tail when engaged by the bunter on the lay.

The invention and new combination of parts will best be made clear from the following description and the accompanying drawings of one good form thereof.

In the drawings:

Fig. 1 is a sectional side elevation of a loom provided with the present invention; and

Fig. 2 is an enlarged perspective view of the dog and its associated parts.

The loom to which the present invention is applied may be of the usual commercial type, comprising loom sides 1, the lay 2, carried by the swords 3 and actuated through a pitman 4 from the crank shaft 5

journaled in suitable bearings in the loom sides.

The main parts of the warp stop mechanism comprise the usual warp supports 6, as shown, between which are mounted the drop wires 7, which may be of any usual type, and herein shown as guided in their movements by the guide bars 8 which pass through slots 9 of the drop wires. The warp threads *a* normally support the drop wires 7 during normal loom operation and to this end each drop wire is shown as having an opening 10 for the passage of a warp thread. These parts may be of any usual character now common in warp stop mechanisms.

Supported in bearings 11 is a transverse shaft 12 carrying the detector 13 which is given a vibratory movement back and forth, as usual, through an arm 14 connected by a rod 15 with the lever 16 pivotally supported at 17 and normally under the influence of a spring 18 for holding the end 19 of the lever in engagement with a cam 20 on the under or cam shaft 21. These parts may be substantially the same as shown and described in the Brown patent above mentioned.

Mounted in a bearing 22, Fig. 2, which may be conveniently supported by a bracket 23 secured to the loom side is a rock shaft 24 having secured thereto a governor 25 provided with an opening 26 into which projects a pin 27 extending laterally from the dog or fan-tail 28, which is itself mounted upon the rock shaft 24 for sliding movement relative thereto. The dog 28 has a slot 29 through which the shaft 24 extends, the construction being such that the dog 28 may be raised or lowered by the governor 25 and may also be moved backward relative to the shaft 24.

Also mounted on the shaft 24 is the head 30 of the knock-off which, like the dog 28, is provided with a slot whereby it may move lengthwise relative to the shaft 24, and connected to the head 30 is the knock-off rod 31 to effect loom stoppage when the dog, and therefore the knock-off head, are moved backward relative to the shaft 24. Extending from the dog 28 is a pin 32 which enters a slot 33 in the knock-off head, the construction being such that should the dog 28 be

2
moved rearward, as described, the knock-off head 30 will likewise be moved rearward and pull upon the knock-off rod 31. In accordance with the present invention, such 5 pull upon the knock-off rod 31 is utilized to effect loom stoppage, which may be effected by disengaging the shipper from its holding notch or moving it rearward.

In the present instance, the knock-off rod 10 31 is connected with the shipper 34 by a pin and slot connection as at 35, the shipper itself being pivoted to the loom frame at 36, or, if desired, the same character of shipper knock-off may be employed as shown 15 in the Carl D. Brown patent, since the particular details of the knock-off form no essential part of the present invention.

The lay 2 carries a bunter 37 which is adapted to engage the dog 28 on backward 20 movement of the lay provided the dog has been positioned for engagement by the bunter to thereby effect loom stoppage. The parts so far described may be of the same general construction as shown and described 25 in the Carl D. Brown patent, or such construction may be modified within the true scope of the present invention.

The rock shaft 24 has extending therefrom an arm 38 and such arm, in warp stop 30 mechanisms of this general type, is actuated to rock the rock shaft by movement of the detector, in order to carry the dog 28 to a position that it may not be engaged by the bunter 37 so long as the detector partakes of its detecting movement.

Should the dog 28, however, be positioned for engagement by the bunter when the detector is arrested in its detecting movement by a drop wire, it is liable at this time to 40 be given a turning movement as well as its backward movement to effect loom stoppage, and such turning movement of the dog will be transmitted to the detector and increase the pressure thereof against the drop wire. 45 The present invention contemplates means between the detector and dog for relieving the drop wire of such increased or injurious pressure by the detector, and broadly considered, such means consists of the connections between the dog and detector, as will 50 be more fully described.

The detector shaft 12 has extending therefrom an arm 39 to which is connected at 40 a rod 41 yieldingly associated with 55 a lever in the train of connections between the detector and dog. As shown, in the present instance, such connections comprise a bell crank lever pivotally mounted at 42 to a bracket 43 secured to the loom side, one arm 44 of the bell crank lever being connected to a rod or transmister 45 which is joined to the arm 38 extending to the rock shaft 24. The other arm 46 of the bell crank is yieldingly connected to the rod 41, and in the present instance such arm 46

of the bell crank carries a sleeve or collar 47 pivotally mounted at 48 on the arm 46. The rod 41 passes through the sleeve 47 and is provided with the adjustable collars 49, one above and the other below the sleeve 47. 70 The collars 49 may be conveniently secured to the rod 41 in adjusted position by means of the set screws 50 or other convenient means, and between the collars 49 and the sleeve 47 are interposed the springs 51, one above and the other below the sleeve 47, the construction being such that the sleeve 47 connected to the bell crank may have a yielding movement on the rod 41 in either direction, whereby any turning movement of the dog 28 which may be transmitted to the rock shaft 24 through the governor 25 will 75 yieldingly act through the described means upon the detector and relieve the drop wire engaged thereby from injurious pressure. 80

Ordinarily the dog 28 is so contrived and positioned that when engaged by the bunter on the lay the central portion of the dog will contact with the bunter and the dog be moved directly in a transverse direction 90 relative to the shaft 24, but owing to the wear of the parts and inaccuracy of adjustment it may happen at times that the dog will be engaged by the bunter at a point either above or below its longitudinal center, with the result that as the bunter moves rearward the dog will not only be given its transverse movement relative to the rock shaft but will be given a turning movement 95 which will be transmitted through the governor to the rock shaft 24, and perforce impart to the detector increased pressure against the drop wire, should yielding means not be provided between the detector and dog. 100

Should the detector be arrested in the position indicated in Fig. 1 and the dog be engaged by the bunter at a point above its longitudinal center, the bell crank lever carrying the sleeve 47 will be raised to thereby relieve the pressure of the detector against the drop wire, and it may in some cases impart sufficient movement to the detector to cause disengagement from the drop wire which has arrested its movement. This, 110 however, does not effect the loom stoppage, because the dog at such times has already been engaged by the bunter. On the other hand, should the dog be engaged by the bunter at a point below the longitudinal center, then the turning movement of the rock shaft 24 will be transmitted to the detector yieldingly, in the disposition of parts shown by Fig. 1, to avoid injurious crushing pressure of the detector against the drop wire. 120

From the construction described it will be apparent that the present invention provides connections between the dog and detector of a yielding nature to prevent injurious 125

crushing pressure of the detector against a drop wire when the detector is arrested in its movement and the dog itself has been engaged by the bunter at a point either 5 above or below its longitudinal center.

What is claimed is:

1. In a warp stop mechanism for looms, the combination of a series of drop wires, a detector, means for imparting detecting 10 movement thereto, the lay having a bunter, a dog for cooperation therewith, stopping means operated by the dog when it is engaged by the bunter, connections between the dog and detector independent of the operating means for moving the dog on each detecting movement of the detector and arresting the dog for engagement by the bunter when the detector is arrested by a drop wire, and means in said connections for 15 relieving the drop wire from injurious pressure by the detector due to movement of the dog by the bunter.

2. In a warp stop mechanism for looms, the combination of a series of drop wires, a 20 detector, means for imparting detecting movement thereto, the lay having a bunter, a dog for cooperation therewith on backward movement of the lay, stopping means operated by the dog when it is engaged by the bunter, connections between the dog and detector for moving the dog on each detecting movement of the detector and arresting the dog for engagement by the bunter when the detector is arrested by a drop wire, and means including a spring in said connections 25 for relieving the drop wire from injurious pressure by the detector due to movement of the dog by the bunter.

3. In a warp stop mechanism for looms, 30 the combination of a series of drop wires, a detector, means for vibrating the detector, the lay having a bunter, a rock shaft, a dog on said rock shaft adapted to be engaged by the bunter on backward movement of the lay, stopping means operated by the dog when 35 engaged by the bunter, connections between the rock shaft and detector for moving the dog on each detecting movement of the detector and arresting the dog for engagement by the bunter when the detector is arrested by a drop wire, and yielding means in said 40 connections between the dog and detector independent of the detector vibrating means for relieving the drop wire from pressure of the detector when said connections are moved by the dog due to the action of the bunter.

4. In a warp stop mechanism for looms, 45 the combination of a series of drop wires, a detector, means for vibrating the detector, the lay having a bunter, a rock shaft, a dog on said rock shaft adapted to be engaged by the bunter, stopping means operated by the dog when engaged by the bunter on backward movement of the lay, connections between the rock shaft and detector independ- 50

ent of the detector vibrating means for moving the dog on each detecting movement of the detector and arresting the dog for engagement by the bunter when the detector is arrested by a drop wire, and yielding 70 means acting in either of two directions in said connections for relieving the drop wire from pressure of the detector when said connections are moved by the dog due to the action of the bunter. 75

5. In a warp stop mechanism for looms, the combination of a series of drop wires, a detector having a detecting movement and adapted to be arrested by a drop wire, a bunter carried by the lay, a slidably mounted dog in cooperative relation with the bunter, connections between the detector and dog for positioning the latter for engagement by the bunter when the detector is arrested by a drop wire, and yielding means 80 in said connections for relieving the drop wire from injurious pressure of the detector due to movement of the dog after it has been engaged by the bunter. 85

6. In a warp stop mechanism for looms, 90 the combination of a series of drop wires, a detector, means for vibrating the detector, a bunter carried by the lay, a dog for engagement by the bunter on backward movement of the lay, stopping means connected 95 to the dog, a rock shaft on which the dog is mounted, connections between the rock shaft and detector independent of the detector vibrating means for moving the dog on each detecting movement of the detector and arresting the dog for engagement by the bunter when the detector is arrested by a drop wire, such connections including a 100 yielding member operatively connected to the detector to cushion the pressure of the detector against the drop wire when the rock shaft is turned by movement of the dog when engaged with the bunter. 105

7. In a drop wire mechanism for looms, 110 the combination of a series of drop wires, a detector, means for imparting detecting movement thereto, a rock shaft, a dog connected to the rock shaft and having a movement towards and from the front of the loom, a bunter on the lay, stopping mechanism actuated by the dog when moved by the bunter as the lay goes back, an arm secured to the rock shaft, a lever for operating the arm and rock shaft, and yielding 115 connections between the lever and detector independent of the detector moving means for relieving the pressure of the detector against a drop wire when the rock shaft is turned by the dog due to the action of the bunter. 120

8. In a warp stop mechanism for looms, 125 the combination of a series of drop wires, a detector, means for vibrating the detector, an arm connected to the detector, a rod extending from the arm, a sleeve on the rod, 130

4

springs interposed between the sleeve and rod, a dog, the lay having a bunter to co-operate with the dog to effect loom stoppage on the occurrence of a warp fault, and 5 connections between the sleeve and dog for yieldingly controlling the position of the dog.

9. In a warp stop mechanism for looms, the combination of the lay having a bunter, 10 a series of drop wires, a vibrating detector to engage and be arrested by a drop wire, a pivotally and slidably mounted dog to co-operate with the bunter to effect loom stoppage, an oscillating governor connected to 15 the dog, means connected to the detector for rendering the governor effective to position the dog for engagement by the bunter on the occurrence of a warp fault, said means including a rod movable longitudinally by vibration of the detector, and a

yielding connection between said rod and the governor to relieve the drop wire of pressure when the dog is moved pivotally by engagement with the bunter.

10. In a warp stop mechanism for looms, 25 the combination of a series of drop wires, a detector, means for vibrating the detector, a rod moved longitudinally by movement of the detector, a sleeve loosely mounted on the rod, a spring on the rod at each side of 30 said sleeve, means for adjusting the action of said springs, a lever connected to the sleeve, a rock shaft, a dog on the rock shaft, the lay having a bunter for engaging the dog on the occurrence of a warp fault, and 35 connections between the dog and lever.

In testimony whereof, we have signed our names to this specification.

GEORGE W. REID.
ALFRED DURAND.
